UNITED STATES PATENT OFFICE.

PATRICK ALPHONSUS MARTIN, OF BIRMINGHAM, ENGLAND.

MANUFACTURE OF GOLF-BALLS.

SPECIFICATION forming part of Letters Patent No. 745,213, dated November 24, 1903.

Application filed September 8, 1903. Serial No. 172,362. (No model.)

To all whom it may concern:

Be it known that I, PATRICK ALPHONSUS MARTIN, manufacturer, a subject of the King of Great Britain, residing in Granville street, 5 Birmingham, England, have invented certain new and useful Improvements in the Manufacture of Golf-Balls, of which the following is a specification.

This invention has relation to the manufacture or production of golf and analogous balls of that type in which a rubber or other elastic core is inclosed in an outer casing or shell of gutta-percha or like material, and refers in particular to an improved method or 15 process of closing the said shell or outer covering around the core, whereby I obtain a solid-closed and seamless cover which is not liable to crack or split and be rendered useless when the ball is in play, as frequently 20 happens with balls having seamed coverings, which are usually made from two hemispherical shells united together at their edges, so that the ball has a circumferential seam in the outer cover; but according to the present 25 invention the core of the ball is inclosed in a single or one-piece covering or shell of a cup-like form, the mouth of which is closed over or onto the core in such a manner that a solid-closed and perfectly homogeneous covering 30 devoid of external and internal seams or flaws is obtained, the said closing-over process being performed in a special manner, as hereinafter described with reference to the accompanying drawings, in which—

35 Figure 1 represents a section of the finished ball. Fig. 2 shows the one-piece cup-like shell from which the covering is made, with the core placed in the bottom of same. Figs. 3 to 7 show the various stages or steps involved in the process of solid-closing the mouth of the cup and obtaining a perfectly 40 seamless or solid covering.

45 *a* is the tensioned rubber or other resilient core of the ball, and *b* is the one-piece covering or outer case, which is made from gutta-percha or other similar material. *c* is the cup-like shell from which the said one-piece covering is made, and *c'* is the open mouth thereof, this shell preferably containing 50 slightly more material than is actually required for the formation of a covering of the

desired thickness. In the process of making up the ball the cup-like shell is first softened by the application of gentle heat, such as by immersing same in hot water, and then the core 55 is forced into the inside of the said shell and bedded down into the hemispherical bottom thereof, so as to make a dead fit therein, as shown in Fig. 2.

While the shell is still in a soft condition 60 the material contained in the upright walls *c*², surrounding the mouth, is manipulated and stretched or drawn upward and also simultaneously gathered in, contracted, or circumferentially throttled at a point below the upper edge of the cup, so as to make the said material take a configuration resembling that of a trumpet-mouth or the mouth of a sack, and thus the shell is brought almost completely over the top of the core, as represented 70 in Fig. 3. Next the inside and throat *c*³ *c*⁴ of the gathered-in portion of the shell is "fired" or superficially melted by momentarily applying a spirit-flame or other jet thereto, and the closing in or shutting over of the 75 material upon the core is completed by pinching together the walls thereof, when consequent upon the melted condition of the inner parts the meeting surfaces of the said walls are homogeneously united and the said 80 core is completely inclosed. The closed-over portion of the material is next further manipulated or molded into a solid conoidal form, a represented in the sectional view Fig. 4 and marked *c*⁵, whose apex is drawn 85 out or twisted into a stem *c*⁶, having at the tip end a lump of superfluous material, such as *c*⁷, which is subsequently broken off or removed, as shown in Fig. 5, and any small seam which may remain or be present in the 90 apex of the coned portion is sealed or closed by melting the material at this point by a flame-jet or otherwise, when the solid-closed shell now has the pear-shaped appearance represented in elevation in Fig. 6.

95 The stretching and gathering up and solid-closing of the walls of the upper portion of the cup-like shell in the manner described has the effect of slightly thinning the walls of said upper portion by displacing some of 100 the material therefrom into the solid conoidal crown; but in the final stage of the process

in order to restore this displaced material to the said upper walls and equalize the thickness of the covering throughout, in addition to imparting the true spherical form to the ball, the pear-shaped body, as represented in Fig. 6, is placed between and operated upon by suitable dies or tools designed to act upon the conoidal portion of the covering in the direction of its major axis and force the material thereof back into the walls of the said covering, which are thus given a uniform thickness, and any superfluous material that may be present in the covering is spread out between the surfaces of the dies into an annular flash or circumferential fin d , (see the elevation of the shaped ball, Fig. 7,) which is subsequently removed by a clipping process.

Having fully described my invention, what I desire to claim and secure by Letters Patent is—

1. In the manufacture of golf and like balls of the rubber-core type; making the coverings or casings from a single solid or one-piece shell of a cup-like section, the mouth of

which is solid-closed or shut over upon the inserted core, substantially as herein described.

2. In the manufacture of golf and like balls of the rubber-core type; making the coverings or casings from a single solid or one-piece shell of a cup-like section the mouth of which is solid-closed or shut over onto the inserted core by gathering in or circumferentially contracting and displacing the material at the side walls of the said cup and uniting the meeting surfaces, thereby completely inclosing the core and forming a homogeneous thickened or conoidal portion, which is subsequently forced back and the walls of the covering equalized in thickness by the action of dies or tools, substantially as and for the purpose herein described and set forth.

In testimony whereof I have hereunto set my hand in presence of two subscribing witnesses.

PATRICK ALPHONSUS MARTIN.
